AUTOMATIC PHONOGRAPH

Samuel Kohn, New York, N. Y., assignor to Radio Corporation of America, New York, N. Y., a corporation of Delaware

Application March 31, 1936, Serial No. 71,910

24 Claims. (Cl. 274—10)

This invention relates to phonographs, and more particularly to an automatic phonograph of the type wherein a plurality of records are stacked upon the turntable for successive reproduction.

5 Heretofore, automatic phonographs of this type have been arranged to play each record in succession and to remove each record from the stack, in turn, to a record receptacle at the completion of playing thereof. Thus, after all of the records 10 have been played once, it is necessary to reload the turntable to provide another record stack thereon. In other words, phonographs of this type are automatic only in the sense that each record of the stack is played in its turn until all 15 of the records have been played, after which the machine requires the attention of the operator for continued automatic operation.

The primary object of my present invention is to provide an improved phonograph of the type 20 set forth which will not only automatically play the entire repertoire once, but which will continue to do so thereafter without requiring reloading or any attention whatsoever on the part of the operator, thereby being a truly continuously 25 playing, automatic phonograph.

More specifically, it is an object of my invention to provide an improved automatic phonograph of the type set forth which, when once set in operation, will continue to play the entire repertoire of records and then repeat the repertoire 30 indefinitely, or until the power is shut off.

Another object of my invention is to provide an improved phonograph of the type mentioned wherein records are interchanged within the stack 35 itself to present a new record for playing.

Still another object of my invention is to provide an improved phonograph of the type specified which may be easily and quickly converted from an automatic machine to a manually operable 40 machine, and vice versa.

A further object of my invention is to provide an improved automatic phonograph as aforesaid which can be preset to play records of various sizes.

45 Still a further object of my invention is to provide an improved automatic phonograph of the type set forth wherein the records are all played from the same level.

An additional object of my invention is to provide an improved phonograph of the type described which will operate satisfactorily with any records having any of the standard terminal grooves of present day commercial records.

It is also an object of my invention to provide 50 an improved phonograph as aforesaid which

is very compact and may be housed within a relatively small cabinet.

It is a further object of my invention to provide an improved phonograph of the type set forth which is very accurate and highly efficient in 5 operation, which comprises a minimum number of operating parts consistent with such operation, and which is relatively inexpensive to manufacture.

In accordance with my present invention, I 10 provide the turntable with a motor driven spindle which extends sufficiently above the turntable to have a plurality of disc records threaded thereon. At the completion of playing of the topmost record, mechanism is set into operation which 15 raises the entire stack of records above the turntable and threads all of the records onto a centering spindle substantially axially aligned with the turntable spindle, after which the centering spindle is withdrawn slightly to leave the lowermost record of the stack free to be removed. A transfer arm then removes the lowermost record 20 from the stack, whereupon the remaining records of the stack are lowered back onto the turntable and the transfer arm brings the removed record 25 over to the top of the stack to present a new playing surface to the record scanning element. Since the successive lowermost records are only temporarily removed from the stack and are immediately returned thereto in the manner described, 30 the total number of records in the stack remains constant once the repertoire is arranged, and an endless series of records is therefore provided. Thus, my improved phonograph will automatically 35 play records continuously and indefinitely, or until the power is shut off. By means of an appropriate indexing device, the automatic mechanism can not only be set to play records of various diameters, but it can also be rendered temporarily ineffective to perform the steps outlined above, whereby records may be played manually.

The novel features that I consider characteristic of my invention are set forth with particularity in the appended claims. The invention 45 itself, however, both as to its organization and method of operation, together with additional objects and advantages thereof, will best be understood from the following description of one embodiment thereof, when read in connection with 50 the accompanying drawings in which

Figure 1 is a top plan view of one form of my invention showing, in solid lines, the position of the parts at the beginning of the playing of a record and with the index mechanism in 10" 55

position, and in dot-dash lines the position of the parts after the record has been played and the lowermost record of the stack has been removed, the record transfer arm being shown, in the latter position, just prior to its return movement to return the lowermost record to the top of the stack.

Fig. 2 is a side elevation of the structure of Fig. 1 viewed approximately from the plane 10 II-II,

Fig. 3 is a similar view showing the position of the parts corresponding to the dot-dash line position of Fig. 1 and with certain of the parts removed for the sake of clearness.

Fig. 4 is a plan view showing the details of the tone arm controlled tripping mechanism, the record transfer arm operating mechanism, and the record lifting mechanism, the parts all being shown in the position they occupy at approximately the beginning of playing of a record,

Fig. 5 is a fragmentary detail view of the tripping mechanism and the record transfer arm operating mechanism in the position it occupies corresponding approximately to the dot-dash line 25 position of Fig. 1.

Fig. 6 is a sectional view taken on the line VI-VI of Fig. 1 and showing the parts in the full line position of Fig. 1.

Fig. 7 is a fragmentary elevation of the mechanism shown in Fig. 6, but with the parts corresponding to the dot-dash line position of Fig. 1.

Fig. 8 is a central section taken on the line VIII-VIII of Fig. 1.

Fig. 9 is a fragmentary plan view of the pick-up arm returning mechanism.

Fig. 10 is a sectional view taken on the line X-X of Fig. 7.

Fig. 11 is a sectional view taken on the line XI-XI of Fig. 1, and

Fig. 12 is a view partly in elevation and partly in section taken on the line XII-XII of Fig. 4.

Referring more specifically to the drawings, wherein similar reference characters designate corresponding parts throughout, there is shown a 45 motor board 1 supporting a motor 3 which drives a spindle 5 on which a turntable 7 is mounted, the spindle 5 having driving engagement with the turntable. The spindle 5 extends above the turntable 7 a distance sufficient to threadedly receive a plurality of disc records 9 which are supported on the turntable for successive reproduction by a suitable record scanning element or sound reproducing instrumentation, such as an electrical pick-up 11, and an associated amplifier and loud speaker (not shown) in a manner hereinafter more fully described.

The pick-up device 11 is carried by a supporting arm 13 which is pivotally mounted at 15 on a collar 17 frictionally fitted on a vertical shaft 19 for movement therewith. To the lower end of the shaft 19 is also fixed, as by means of a collar 21 and a set screw 23, an arm 25 carrying, at its free end, an upwardly extending pin 26. It will be clear, therefore, that the arm 13 and its pick-up 11 can move in a vertical direction about the pivot pin 15 and in a horizontal direction on the shaft 19, the arm 13 carrying with it the arm 25 in the latter movement.

The shaft 19 is rotatable in a bushing 27 which 70 is itself rotatably carried by a standard 29 fixed to the motor board 1 at one side of the turntable, as by a plurality of screws 31. The standard 29 is provided with a pair of spaced, rearwardly extending walls 33 and a pair of rear 75 lugs 35, and also has an annular recess 37 at its

upper end. Force fit upon the upper end of the bushing 27 for rotation therewith and fitted within the annular recess 37, but spaced therefrom by a suitable washer 38, is a collar 39 formed integrally on a record transfer arm 41. The arm 41 is also provided with an annular track 43 which terminates in an inclined cam portion 45 and with a stepped portion 47 which, adjacent to the cam 45, is provided with an aperture 49, while the rear wall of the track 43 is formed with a channel 51 for a purpose presently to be set forth. The other, or record engaging, edge of the arm 41 is provided with a pair of rollers 53 and an overhanging finger piece 55 between which and the arm 41 is carried a spring 57, the arrangement being such that a record disc can pass over the rollers 53 and in between the spring 57 and the finger piece 55 whereby it is firmly gripped, as clearly shown in Fig. 11.

The walls 33 carry a pin 59 on which an arm 61 is pivotally mounted for movement in a vertical plane toward and away from the turntable 7, the arm 61 carrying a record centering spindle 63 of somewhat smaller diameter than the spindle 5. When the arm 61 is in lowered position, the spindle 63 is adapted to engage and form an extension of the spindle 5, as clearly shown in Fig. 2, so that, upon elevation of the record stack 9, the records will become threaded on the spindle 63. The arm 61 also carries a 30 roller 65 under which the track 43 is arranged to pass while in engagement therewith during advance of the transfer arm 41; a downwardly extending pin 67 having a head 69 which is received in the aperture 49 when the arm 61 is in 35 lowered position, as shown in Fig. 2, but which is received in the channel 51 while the record transfer arm 41 is advanced, as shown in Figs. 6 and 7; and an upwardly extending pin 71 for engaging the pick-up arm 13. Pivoted between 40 the lugs 35 is a latch plate 73 which is connected to the arm 61 by a coil spring 75, the rear end of the arm 61 having a detent 77 adjustably secured thereto by means of the screws 78 for cooperation with the toes 79 and 81 of the plate 73. The 45 screws 78 may be initially adjusted so that when the detent engages the toe 79 (Fig. 6), the arm 61 is in its lowered position with the spindle 63 engaging the spindle 5, as shown in Fig. 2, but when the arm 61 is raised until the detent 77 has 50 passed the toe 81 into the dwell 82, the toe 81 will hold the arm 61 in elevated position so that the record stack 9 may be easily threaded on or removed from the turntable spindle 5. Such movement of the arm 61 on the pin 59 is possible 55 by reason of the fact that the arm 61 is provided with an enlarged hole 62 through which the collar 17 extends.

For operating the mechanism heretofore described and for controlling the cycle of automatic 60 operations, there is provided a member 83 which terminates in an offset tail piece 85 at one end and which has a lateral extension 86 adjacent its other end 87. The member 83 is slidably mounted on a pair of studs 89 which are fixed to the 65 motor board 1 and extend through the slots 91, the member 83 being held against the studs 89 by a plate 93 and screws 95, as clearly shown in Fig. 12. A leaf spring 97 fixed to the plate 93 presses against the member 83 with sufficient force to 70 keep it from sliding around loosely, while one of the slots 91 is provided with a cam surface 92 for a purpose shortly to be described.

Pivoted on the end 87 of the member 83 is a trip lever 99 which terminates in an arcuate sur- 75

face 101 with which a downwardly extending pin or lug 103 on a gear 105 is arranged to cooperate. The gear 105 is driven from a gear 107 on the spindle 5 and preferably has a 5:1 ratio therewith so that the gear 105 makes one revolution for every five revolutions of the turntable. During travel of the pick-up 11 over the record being played, the pick-up arm 13 and the arm 25 move together horizontally and the pin 26 engages the end 100 of the trip lever 99 and moves it counterclockwise (as seen in Fig. 4) about its pivot 102, thus bringing the arcuate portion 101 into the path of the lug 103. At every fifth revolution of the turntable 7, the lug 103 engages the surface 101 and cams the lever 99 back somewhat in a clockwise direction about the pin 26, since the end 100 is now engaged by the pin 26. This results in a slight forward advance of the slideable member 83 in the direction of the arrow A, and further advance of the member 83 takes place with each alternate counterclockwise and clockwise movement of the lever 99.

Carried by the lever 99 adjacent the arcuate edge 101 for limited pivotal movement thereon is a bellcrank 109 having a shoulder 111 and terminating in an end portion 113 adapted to engage a fixed stop 115 secured to the lower surface of the motorboard 1. During playing of the record, the bellcrank 109 occupies the position shown in Fig. 4 under the influence of a small, weak spring (omitted for the sake of clearness). If the record being played has a rapid lead-in groove terminating in either a concentric or an eccentric terminal groove, the pickup 11, its arm 13 and the arm 25 will be given a quick inward movement when that groove is reached and the pin 26 will rotate the lever 99 counterclockwise about the pivot 102 through an angle sufficient to cause the end 113 of the bellcrank 109 to abut 40 against the stop 115. This causes the bellcrank 109 to rotate in a clockwise direction to bring the shoulder 111 into the path of the lug 103 to initiate a cycle of automatic operations in the manner shortly to be set forth. If the record 45 being played happens to terminate in a concentric terminal groove and does not have a rapid lead-in groove, counter-clockwise rotation of the lever 99 on its pivot 102 will cease as soon as the stylus has entered the terminal groove. However, continued rotation of the gear 105 will eventually cause the lug 103 to rotate the lever 99 about the pin 26 an amount sufficient to cause advancement of the member 83 until the cam surface 92 has passed its stud 89. At this point, the spring 97 50 imparts a counterclockwise rotation of the member 83 about its other stud 89 an amount sufficient to interpose the shoulder 111 in the path of the lug 103. Thus, regardless of the type of record being played, engagement of the lug 103 with the shoulder 111 must eventually be effected.

As soon as the lug 103 has tripped the lever 99 in the manner heretofore described, a spring blade 117 engages an upwardly extending pin 119 on a master cam 121 and gives the cam 121 a clockwise rotation sufficient to cause engagement of the periphery thereof with a friction gear 123 which may be fixed to the gear 105 for rotation therewith, whereby rotation of the cam 121 is continued. The master cam 121, which is rotatably carried by a slide bar 125, is provided with a rise between the points B and C, thereafter has its periphery concentric with its axis of rotation until approximately the point D, after which it has a gradual drop until the point B, at which 75 point it takes a sharp drop, so that the cam 121

may be out of engagement with the friction gear 123 during playing of a record. As the cam 121 rotates, the rise B-C forces it away from the gear 123 and moves the slide bar 125 in the direction of the arrow E (Fig. 4).

Fixed to the motorboard 1 is a downwardly extending bracket 127 on which is pivotally mounted a yoke member 129 having its ends 131 bifurcated. Each end 131 is laterally slotted to receive a plate 133 which is provided with an elongated slot 135 through which a post 137 extends, each post 137 having a pin 139 extending therethrough and received by the plates 133 so that, as the yoke 129 is raised, the post 137 can pivot relative thereto. An upstanding pin 141 on the slide bar 125 engages a cross pin 143 on the yoke 129 and imparts counterclockwise movement to the yoke 129, as viewed in Fig. 2, whereby the posts 137 are elevated. The posts 137 are slideable in bearings 145 and are located on diametrically opposite sides of the turntable 7, one of the posts 137 carrying at its upper end a record engaging member 147, and the other post 137 carrying at its upper end a record engaging member 148, the members 147 and 148 occupying a position below the surface of the turntable during playing of a record, as clearly shown in Fig. 2. When the posts 137 are raised in the manner heretofore described, the members 147 and 148 engage the projecting edges of the lowermost record 30 of the stack and elevate the entire stack well above the turntable to the position shown in Fig. 3.

Shortly after the master cam 121 commences to rotate, an eccentric pin 151 thereon engages a rack 153 which is pivotally mounted on the motor board at 155 and causes it to rotate counterclockwise, as viewed in Fig. 4, to produce clockwise rotation of a gear 157 in mesh therewith. The gear 157 is force fit onto the lower end of the bushing 27, so that rotation thereof in the manner just described causes the record transfer arm 41 to move from its solid line position of Fig. 1 toward the record stack. This takes place after the records have been elevated to a position such that the lowermost record of the stack is in the plane of movement of the arm 41. As soon as the arm 41 begins its movement toward the record stack, the cam surface 45 rides under the roller 65 and raises the arm 61 a distance sufficient to withdraw the center pin 63 from the center hole of the lowermost record, at the same time causing withdrawal of the pin 67 from the aperture 49, whereby the head 69 thereof is adapted to be received within the channel 51 to 55 further limit relative movement between the arms 41 and 61.

When the arm 41 reaches the record stack, the rollers 53 thereof engage the lower surface of the record, while the forward edge of the finger piece 55 engages the edge of the lowermost record and pushes it away from the stack until it engages a stop bar 159 secured to the motor board 1, whereupon the record is forced in between the finger piece 55 and spring 57. The arm 41 then advances to the dot and dash line position of Fig. 1 to remove the lowermost record entirely clear of the stack.

When the arm 41 begins its forward movement, the pin 71 on the arm 61 engages the pick-up arm 13 and raises it slightly above the topmost record so that upon subsequent return of the pick-up arm to starting position, the needle will not scratch the topmost record. The lower surface of the pick-up arm 13 is formed with a gradual 75

incline 13a which the upper end of the pin 42 on the arm 41 engages as the arm 41 moves forward. This further gradually raises the pickup arm until the pin 42 has moved past the sharp incline 13b on the pickup arm. On the return movement of the record transfer arm 41, the pin 42 engages the sharp incline 13b and moves the pick-up arm back to starting position, as determined by the index mechanism hereinafter to be described, after which the continued movement of the arm 41 causes the pin 42 to slide past the incline 13b and back to its normal, or rest, position.

Return of the record transfer arm 41 to normal position is produced by engagement of the pin 119 of the master cam 121 with a lever 161 which is pivotally mounted on the motorboard 1 and which has a slot 163 therein for the reception of a downwardly extending pin 165 on the rack 153. The pin 119 imparts counterclockwise rotation to the lever 161 which, in turn, imparts clockwise rotation to the rack 153 about its pivot, 155, and this, in turn, produces counterclockwise rotation to the gear 157 and its associated record transfer arm 41. As the pickup arm 13 is returned to starting position, the arm 25 is, of course, returned with it, and the pin 26 engages the member 83 to return it to starting position. At the same time, an upstanding lug 167 on the gear 157 engages the adjacent end of a lever 169 which is pivotally carried by the extension 87 and moves it slightly in a clockwise direction to cause it to engage the pin 26 and positively bring the stylus of the pickup 11 into the starting groove of the new record. Movement of the lever 169 is limited by a downwardly extending lug 170 thereon which cooperates with a pair of stops 172 on the extension 86.

Between the time that the arm 41 has reached its dot-and-dash line position and the time it has returned to its solid line, or rest, position of Fig. 1, the cam 121 has rotated sufficiently to bring the point D thereof in engagement with the friction wheel 123. The weight of the records 45 and the turntable then causes the posts 137 to lower under the influence of gravity, thereby lowering the yoke 129 and returning the slide bar 125 to its rest position, and when the cam 121 has rotated until the point B leaves the friction gear 123, the sudden drop at this point causes sudden disengagement of the cam 121 from the friction gear 123, whereupon the parts all remain in rest position and the playing of the next record is ready to be commenced. This 55 next record is the one which the transfer arm 41 has returned to the top of the stack after the stack has been lowered back onto the turntable 7, having been freed from the transfer arm 41 by a pair of stops 171 of the aforesaid index mechanism which centers it properly with respect to the stack.

The index mechanism comprises a hollow standard 173 fixed to the motor board 1 and through which a shaft 175 extends, the shaft 175 being longer than the standard 173 and having a pair of cams 177 and 178 fixed thereto. Pivotally mounted on the top of the standard 173 is a pair of cooperable indexing arms 179 upon which the stops 171 are carried. A coil spring 181 constantly tends to maintain the indexing arms separated, and the extent of their separation is controlled by the cam 177. By manipulating a thumb screw 183, fixed to the upper end of the shaft 175, the cams 177 and 178 may 75 either be set in the 10-inch position, as shown in

Figs. 1 and 4, turned clockwise 90° to set the mechanism for automatic 12-inch operation, or turned 180° for manual operation. It will be noted that the cam 178 has the cam portions 178a, 178b and 178c at different radial distances from the shaft 175. This enables determining the extent to which the pin 26 will return the slide member 83, and thus, also, determining the position to which the pickup arm 13 is returned, depending upon the diameter of the records of the stack. In the manual position, the cam portion 178a engages the edge 82 of member 83 and advances the slide member 83 in the direction of the arrow A a distance such that the pin 26 does not at any time engage the end 100 of the trip lever 99. Consequently, the automatic mechanism cannot be set into operation. An index plate 185 fixed to the standard 173 may be marked with the designations "10", "12", and "M" with which a suitable pointer on the thumb screw 183 may cooperate for visibly indicating the position in which the shaft 175 and its associated cams 177 and 178 are to be set for the particular operation desired.

From the foregoing description, it will be apparent that I have provided an improved phonograph which may be operated either automatically or manually, at will, and which, in automatic operation, will continuously play a repertoire of records through and through. The record elevating members 147 and 148 provide a 3-point support for the stack of records, which, together with the pin 49 and the relation of the head 69 thereof with the channel 51, insures proper removal of the lowermost record of the stack regardless of whether it is warped or not. It is believed that this, as well as many other advantages of my invention, will be apparent from the foregoing description. Also, it will undoubtedly be obvious to those skilled in the art 40 that many changes in and modifications of the specific form of my invention herein described may be made without departing from the spirit thereof, it being essential, merely, that the record stack be separated from the turntable at the 45 proper point in the cycle during automatic operation, and that the records be interchanged within the stack for repeated playing. I desire, therefore, that my invention shall not be limited except insofar as is made necessary by the prior 50 art and by the spirit of the appended claims.

I claim:

1. In a phonograph of the type wherein a plurality of records are stacked upon the turntable for successive reproduction, the combination of means for reproducing the topmost record of the stack, and means effective at the completion of playing of said record to remove another record from said stack and place it on the top thereof to present a new record for 60 playing.

2. In a phonograph of the type wherein a plurality of records are stacked upon the turntable for successive reproduction, the combination of means for reproducing the topmost record of the stack, and means effective at the completion of playing of said record to remove the lowermost record from said stack and place it on the top thereof to present a new record for playing.

3. In a phonograph of the type wherein a plurality of records are stacked upon the turntable for successive reproduction, the combination of means for reproducing the successive topmost records of the stack, means for separating the stack from the turntable upon completion of 75

playing of each record, and means for removing the lowermost record from the stack while said stack and said turntable are in separated relation and for subsequently replacing said record on the top of the stack whereby to present a new record for playing.

4. In a phonograph of the type wherein a plurality of records are stacked upon the turntable for successive reproduction, the combination of means for reproducing the successive topmost records of the stack, means for raising the stack above the turntable upon completion of reproduction of each record, and means for removing from the raised stack the lowermost record and for subsequently replacing said record on the top of the stack whereby to present a new record for playing.

5. In a phonograph of the type wherein a plurality of records are stacked upon the turntable for successive reproduction, the combination of means for reproducing the successive topmost records of the stack, record elevator means associated with said stack, means effective at the completion of playing of each record to render said elevator means operative to raise the entire stack of records above the turntable, means for removing the lowermost record from the stack when said records are in elevated position, means for causing said records to be lowered back onto said turntable, and means for causing said record removing means to place said removed record on the top of the stack whereby to present a new record for playing.

6. In a phonograph of the type wherein a plurality of records are stacked upon the turntable for successive reproduction, the combination of means for reproducing the successive topmost records of the stack, means for separating the stack from the turntable at the completion of playing of each record, means for removing one of the records of the stack clear of the stack while said stack and said turntable are in separated relation, means for causing said stack to be reunited with said turntable after said one record has been removed therefrom, and means for causing said removed record to be placed on the top of the stack whereby to present a new record for playing.

7. In a phonograph of the type wherein a plurality of records are stacked upon a turntable for successive reproduction, the combination of means for reproducing the successive topmost records of the stack, means for separating the stack from the turntable at the completion of playing of each record, means for removing the lowermost record of the stack clear of the stack while said stack and said turntable are in separated relation, means for causing said stack to be reunited with said turntable after said lowermost record has been removed therefrom, and means for causing said removed record to be placed on the top of the stack whereby to present a new record for playing.

8. In a phonograph of the type wherein a plurality of records are stacked upon the turntable for successive reproduction, the combination of means for reproducing the successive topmost records of the stack, means for elevating the stack above the turntable at the completion of playing of each record, means for removing the then lowermost record of the stack clear of the stack while said stack is in elevated position, means for causing said stack to be lowered back onto said turntable after said lowermost record has been removed from the stack, and means

for causing said removed record to be placed on the top of the stack whereby to present a new record for playing.

9. The invention set forth in claim 8 characterized in that said record elevating means is arranged to elevate said stack to a position such that the lowermost record thereof occupies a level above that of the topmost record when the stack is lowered back onto the turntable.

10. The invention set forth in claim 8 characterized by the addition of means adapted to cooperate with the removed record for centering said record coaxially with the other records of the stack.

11. The invention set forth in claim 8 characterized by the addition of means adapted to cooperate with the removed record for centering said record coaxially with the other records of the stack and characterized further in that said last named means comprises an adjustable indexing mechanism which is adjustable to be engaged by records of various diameters.

12. In a phonograph, the combination of a turntable, a plurality of records stacked thereon, a spindle extending upwardly from said turntable a distance sufficient to threadedly receive said plurality of records, an arm pivotally mounted to one side of said turntable for movement toward and away from said turntable and having a centering spindle thereon, said centering spindle being arranged to form an extension of said turntable spindle when said arm is in lowered position, means for elevating the record stack above said turntable spindle whereby to thread the records onto said centering spindle, means for withdrawing said centering spindle from said stack a distance sufficient to clear the lowermost record of the stack, and means for removing said lowermost record from said stack upon withdrawal of said centering spindle therefrom.

13. In a phonograph, the combination of a turntable, a plurality of records stacked thereon, a spindle extending upwardly from said turntable a distance sufficient to threadedly receive said plurality of records, an arm pivotally mounted to one side of said turntable for movement toward and away from said turntable and having a centering spindle thereon, said centering spindle being arranged to form an extension of said turntable spindle when said arm is in lowered position, means for elevating the record stack above said turntable spindle whereby to thread the records onto said centering spindle, means for raising said arm away from said turntable a distance sufficient to withdraw said centering spindle from said stack clear of the lowermost record of the stack, means for removing said lowermost record clear of said stack while said stack is in elevated position, means for causing said stack to be lowered back onto said turntable while said arm is still in raised position, and means for placing said removed record on the top of the stack after said stack has been replaced on the turntable.

14. In a phonograph, the combination of a turntable, a plurality of records stacked thereon, a spindle extending upwardly from said turntable a distance sufficient to threadedly receive said plurality of records, an arm pivotally mounted to one side of said turntable for movement toward and away from said turntable and having a centering spindle thereon, said centering spindle being arranged to form an extension of said turntable spindle when said arm is in lowered position, means for elevating the record stack above said

- turntable spindle whereby to thread the records onto said centering spindle, means for raising said arm away from said turntable a distance sufficient to withdraw said centering spindle from said stack clear of the lowermost record of the stack, means for removing said lowermost record clear of said stack while said stack is in elevated position, means for causing said stack to be lowered back onto said turntable while said arm is still in raised position, means for placing said removed record on the top of the stack after said stack has been replaced on the turntable, and means for thereafter causing said arm to be lowered to its said lowered position.
15. In an automatic phonograph of the type wherein a plurality of records are automatically transferred from an idle position to a sound reproducing position in succession at the completion of playing of each record, the combination of 10 means for reproducing sound from records of various diameters, means for transferring records from said idle position to said sound reproducing position, adjustable indexing means movable manually to any one of a plurality of predetermined 15 positions corresponding to the diameter of records being played, and means cooperatively associated with said index means and with said sound reproducing means and responsive to adjustment of said index means to determine the starting 20 position of said sound reproducing means in accordance with said diameter, said indexing means including record engaging means for locating the record next to be played in said reproducing position.
30. 16. In an automatic phonograph of the type wherein a plurality of records are automatically transferred from an idle position to a sound reproducing position in succession at the completion of playing of each record, the combination of 25 means for reproducing sound from records of various diameters, means for transferring records from said idle position to said sound reproducing position, adjustable indexing means movable manually to any one of a plurality of predetermined 30 positions corresponding to the diameter of records being played, and means cooperatively associated with said index means and with said sound reproducing means and responsive to adjustment of said index means to determine the starting 35 position of said sound reproducing means in accordance with said diameter, said indexing means including record engaging means for locating the record next to be played in said reproducing position.
45. 17. In an automatic phonograph of the type wherein a plurality of records are automatically transferred from an idle position to a sound reproducing position in succession at the completion of playing of each record, the combination of 40 means for reproducing sound from records of various diameters, means for transferring records from said idle position to said sound reproducing position, adjustable indexing means movable manually to any one of a plurality of predetermined 45 positions corresponding to the diameter of records being played, and means cooperatively associated with said index means and with said sound reproducing means and responsive to adjustment of said index means to determine the starting 50 position of said sound reproducing means in accordance with said diameter, said indexing means including record engaging means for locating the record next to be played in said reproducing position.
55. 18. In an automatic phonograph, the combination of a sound reproducing instrumentality, mounted for movement over a record, a continuously rotatable member, a slidable member having a cam surface thereon, a fixed element adapted to be engaged by said cam surface, a lever pivotally carried by said slidable member, means on said continuously rotatable member adapted to engage said lever for actuating said lever, means responsive to actuation of said lever for initiating a cycle of automatic operations including removal of said sound reproducing instrumentality from the record, and means associated with said sound reproducing instrumentality for progressively advancing said slidable member in a direction to cause said lever to be interposed in the path of movement of said first named means, said lever being interposed in said path when said cam surface has been advanced past said fixed member.
19. In an automatic phonograph, a sound reproducing instrumentality mounted for movement over a record, a continuously rotatable member, a slidable member, a lever pivotally carried by said slidable member, means on said continuously rotatable member adapted to engage said lever for actuating said lever, means responsive to actuation of said lever for initiating a cycle of automatic operations including removal of said sound reproducing instrumentality from a record upon completion of playing of said record, means associated with said instrumentality for effecting engagement between said lever and said last named means whereby to initiate said cycle of automatic operations, means arranged to be controlled by said continuously rotatable member for returning said instrumentality to starting position, said last named means including a gear having a fixed relation with said instrumentality, a movable rack member associated with said gear, means associated with said continuously rotatable member for actuating said rack member, a second lever pivotally carried by said slidable member for bringing said instrumentality into engagement with the first groove of the next record to be played, and means on said gear for actuating said second lever to cause it to move said instrumentality into said first groove.
20. In an automatic phonograph of the type wherein a plurality of records are stacked upon the turntable for successive reproduction, a sound reproducing instrumentality, and means including a record transfer arm mounted for movement across said turntable in a fixed horizontal plane and controlled by said instrumentality for slidably removing from the stack one of the records thereof while moving in one direction across said turntable and replacing it in some other place in the stack in relation to said sound reproducing instrumentality while moving in the opposite direction.
21. In an automatic phonograph of the type wherein a plurality of records are stacked upon the turntable for successive reproduction, a sound reproducing instrumentality, and means including a record transfer arm mounted for movement across said turntable in a fixed hori- 75

5 zontal plane and controlled by said instrumentality for slidably removing from the stack one of the records thereof while moving in one direction across said turntable and replacing it in the stack in operative relation to said sound reproducing instrumentality while moving in the opposite direction.

10 22. In an automatic phonograph of the type wherein a plurality of records are stacked upon the turntable for successive reproduction, a sound reproducing instrumentality, means mounted for movement across said turntable and controlled by said instrumentality for removing from the stack one of the records thereof and replacing it in the stack in operative relation to said sound reproducing instrumentality, and means on said 15 last named means for placing said sound reproducing instrumentality in substantially starting position with reference to the record next to be reproduced.

15 23. In an automatic phonograph of the type wherein a plurality of records are stacked upon the turntable for successive reproduction, a sound reproducing instrumentality, a movable stop member, adjustable index means associated with 20 said stop member for determining the starting

position of said sound reproducing instrumentality, means mounted for movement across said turntable and controlled by said instrumentality for removing from the stack one of the records thereof while moving in one direction across said turntable and replacing it in the stack in operative relation to said sound reproducing instrumentality while moving in the opposite direction, and means on said last named means for engaging and moving said sound reproducing instrumentality against said stop member whereby to position said sound reproducing means with reference to the next record to be played.

25 24. The invention set forth in claim 4 characterized in that the means for removing the lowermost record from the stack comprises an arm mounted for movement in a plane above the turntable, and characterized further in that the free end of said arm is provided with a member adapted to engage the periphery of said lowermost record whereby to slightly dislodge said record from the stack as said arm is moved forward, said arm also having record gripping means for gripping the record upon continued movement of said arm in a forward direction. 20 25

SAMUEL KOHN.
